HIGH-PRESSURE RADIAL PISTON PUMP
FOR LIQUIDS

Georges Pauget, Chaville, France, assignor to Societe d'Installation et d'Appareillage, Paris, France

Continuation of application Serial No. 624,028, October 23, 1945. This application October 17, 1950, Serial No. 190,539. In France October 28, 1944

10 Claims. (Cl. 103—5)

1

This patent application is a continuation of my earlier patent application Serial No. 624,028 filed on October 23, 1945, for "High pressure radial piston pumps for liquids," now abandoned, and certain parts of the present application will be found in the earlier application.

The present invention relates to improvements in pumps for liquids and in particular in high pressure radial piston pumps controlled by an eccentric keyed on a central shaft.

The principal object of the invention is to provide, in a pump of the character described, means for automatically and instantaneously discontinuing the pumping action whenever the delivery pressure thereof exceeds a predetermined value, and without necessitating a stopping of the rotation of the shaft of the pump.

A further object of the invention is to provide a structure of the above type in which the discontinuance of the pumping action is obtained by means which operates to immobilize the pistons of the pump in their outermost positions, against the pressure of the resilient means which normally urges them inwardly against the driving eccentric of the pump.

Still another object of the invention is to provide a pump of the above character in which the means for immobilizing the pistons at their outer positions comprises hydraulic elements contained entirely within the pump body and powered by the pressure fluid of the pump itself, whereby it is possible to dispense with the electrical or manometric external controls formerly employed for similar purposes, and whereby the cost and complexity of manufacture and maintenance of the pump is greatly reduced.

According to the present invention, the means for automatically and instantaneously discontinuing the pumping action or automatic checking means are hydraulically controlled by the discharge pressure of the pump so that they become operative when said pressure is in excess of a predetermined value for actuating means immobilizing the pistons in their outermost positions. Said hydraulic control is operated by a double valve having two opposite seats and which is adapted to be suddenly set in operation, one of the chambers of the said valve being placed in communication with the pressure at delivery, while the other chamber is placed in communication with the pressure at suction and the intermediate chamber in which moves the head of said double valve between its two seats is placed in communication with the immobilizing means.

The present invention also includes a certain

2

number of particular features which will appear from the following description referring to the accompanying drawings given by way of example only and wherein:

Figure 1 is an elevation view of a radial piston pump according to the invention with a general cross-section along the vertical plane of symmetry.

Figure 2 is a sectional view through line II—II of Figure 1 showing, at smaller scale, the arrangement of the hydraulic checking device.

Figure 3 is a cross sectional view taken on the line III—III of Fig. 2.

Figure 4 is a view on enlarged scale of the double valve shown in Fig. 3.

Figure 5 is an elevational outer view from the right of Fig. 1 showing the conduits discharging the liquid towards the single collector.

Figure 6 is a cross sectional view taken on the line VI—VI of Fig. 1 at smaller scale.

Figure 7 is a sectional view taken centrally through one of the pumping units comprising an alternative embodiment of an automatic hydraulic checking device in inoperative position.

Figure 8 is a sectional view taken centrally through one of the pumping units comprising another alternative embodiment of an automatic hydraulic checking device in operative position.

In the embodiment shown in Figs. 1 to 6, two pumps are coupled in series, the first pump discharging into the suction of the second one. It is quite clear that the invention is by no means limited to such an embodiment and is applicable in the case of a single-stage pump as well as in the case in which a plurality of pump stages are provided.

As shown in Fig. 1, the pistons 1 of the first pump are of circular cross-section and are provided at their end adjacent the periphery of the casing 2, wherein they are housed, with a shoulder portion 1a in order to allow the action of the hydraulic checking means the operation of which will be described hereinafter.

Pistons 1, for instance six in number, are uniformly spaced within the casing 2 as also are the pistons 3 of the second pump which are respectively disposed in the same radial planes.

The actuation of the pistons 1 and 3 is effected by means of eccentrics 4 and 5, the angular shifting of which has theoretically a value equal to 180°. Said eccentrics are fitted on a driving shaft 6 or are integral with it, and act upon the cambered heads of the various pistons through grooved rings 7 constituting the outer race of

The driving shaft 6, which is subjected to a continuous rotation at uniform angular speed for a definite output of the pump, is supported in bearings 9, 10 and 11, respectively mounted in the casing 2 and made of any suitable metal according to the character of the liquid to be pumped, and also carried by flanges 13 and 12 coaxial with the shaft 6 and tightly secured by means of screws to said casing. Axial play adjustment of the shaft 6 is obtained at its free end, on one hand, by means of a thrust bearing 14 with a double row of balls clamped by a screw 15 provided with an outer cylindrical portion and, on the other hand, by means of a second ball thrust bearing 16 fitted on said screw cylindrical portion and axially blocked by a threaded plug 17 which in turn is screwed and locked, if need be, in a recess of the flange 12.

To allow the liquid discharged by the first pump to flow into the second one, passages 2a are provided adjacent the periphery of the casing 2 in each radial plane containing the pistons 1 and 3.

The pistons 1 are urged back against the outer periphery of the ring 7 located round the eccentric 4 by springs 18 abutting against plugs 18a constituting the head of each cylinder of the first pump and tightly screwed to the casing 2.

The pistons 3 are urged back towards the ring 7 located round the eccentric 5, without the use of springs, by the action of the liquid discharged by the first pump.

This liquid is directed through check valves 71 into the chambers 2b, and thereafter discharged through conduits 2c (Fig. 5), communicating with each other, towards a single collector not shown and connected to the utilization circuit.

The various valves preventing return of the fluid towards the suction are constituted by check valves such as balls 19 the seats of which are provided for the first pump in the inner passages 17 of pistons 1, and for the second pump in plugs 20 closing the cylinders 3a in which reciprocate the pistons 3 and which are to that end tightly secured to the casing 2. When the various valves are open, the balls 19 abut against insert members 21 as shown in Fig. 1. Relief valves 22 are disposed, in a way known per se, at the upper part of cylinders 3c and communicate with radial conduits 2d connected with central chamber 74 for allowing return of excess of fluid towards said central chamber, in the event of seizing of a piston 3 in its outermost position. The spring 22a of each relief valve 22 is so designed that the pressure exerted on said valve is greater than the pressure maintaining the corresponding piston 3 against the cam 7 during the filling of the corresponding cylinder 3a within which reciprocates said piston 3.

The device operates as follows:

The liquid to be pumped is admitted to the center of the casing 2 within the central or suction chamber 74 by conduit 70 contained in a diametral plane comprised between two successive pistons 1 of the first pump, preferably in the diametral plane passing through the checking device which will be described hereinafter (Fig. 3).

The operative cycle of the pump is now studied for an assembly comprising a piston 1 of the first pump and the piston 3 of the second pump which is associated thereto. Assuming said pistons are in the position illustrated in the upper part of Fig. 1, piston 1 has attained its innermost position while piston 3 has reached its outermost

position. The stroke of eccentrics 4 and 5 have the same value and the cross-sections of piston 3 and of the outer part of piston 1 are equal. Both pistons 1 and 3 being in said positions, the liquid fills the inner passage 1f of piston 1, the part of cylinder 1c located on the outside of said piston 1 and the conduit 2a. When shaft 6 rotates, the operative cycle is as follows:

Piston 1 moves towards the periphery of the pump in opposition to the liquid contained in cylinder 1c and in conduit 2a. The clearance existing between the ball 19 of said piston 1 and the walls of its housing in said piston being small, said ball is applied against its seat thus closing the communication between the inner passage 1f and the cylinder 1c. The liquid contained in cylinder 1c and in conduit 2a is put under pressure and pushes back the ball 19 housed in the plug 20 against the stopping member 21; the liquid under pressure fills the part of cylinder 3a located on the outside of piston 3, and applies said piston against the ring 7 while being displaced towards the shaft. Said liquid cannot escape through valve 71, said valve being maintained in closed position by the pressure existing in the utilization circuit with which it is connected and by its own spring, while the ball 22 which cooperates with piston 1 acts as safety device. The relative positions of pistons 1 and 3, balls 19, 71 and 22 remain unchanged as long as pistons 1 and 3 have not respectively attained their outermost and innermost positions.

When piston 1 moves from its outermost position towards the shaft under the action of spring 18, it generates vacuum in the conduit 2a. Said vacuum has for effect to displace the ball 19 of piston 1 towards its stopping member 21, on the one hand, and, on the other hand, to displace the ball 19 of plug 20 against its seat. Such effects are facilitated by the fact that liquid contained in the central chamber 74 is simultaneously admitted within the inner passage of 1f of piston 1, through port 1b, while the liquid contained in the part of cylinder 3a located on the outside of piston 3 is put under pressure by the outwardly directed movement of said piston 3. Simultaneously, the liquid contained in said part of cylinder 3a discharges through valve 71 into conduit 2c. Then, when pistons 1 and 3 come back to their original position, the cycle begins again, the valve 71 being closed by the action of its spring and by the pressure existing in the utilization circuit. For each revolution of shaft 6, said cycle is repeated as many times as the pump contains pairs of associated pistons 1 and 3.

To the discharge collector formed by the conduits 2c is connected a conduit 72 (Figs. 3 and 5), which communicates with a recess 2e formed in the casing 2, while said collector is connected to the utilization circuit through a discharge port 73.

The checking device (Figs. 2 to 4) comprises a double valve 23 having an intermediate head 23a and two opposite shanks 23b and 23c. The diameter of shank 23b is slightly greater than that of shank 23c. Said shanks are further formed on their free ends with portions having triangular cross-section 23e and 23f (Fig. 4). The cylindrical portions of said shanks 23b and 23c move in cylindrical bores of corresponding diameter which are formed in the casing 2. The double valve head 23a is located in a chamber 23d and acts as stop means for the longitudinal displacement of the double valve 23. Said chamber 23d communicates with a passage 2f1 con-

nected with a circular channel 27 formed into the flange 12 and into which open passages 2f which respectively communicate with chambers 2p formed in cylinders 1c between the shoulders 1a of pistons 1 and the shoulders 1g of said cylinders.

The tightness is obtained by the abutment of the double valve head 23a on the lower wall of the chamber 23d and by the accurate penetration of the cylindrical portion of the shank 23c within the corresponding cylindrical bore.

The cylindrical portion of the shank 23b does not penetrate within the corresponding cylindrical bore and the communication between the passages 2g and 2f is obtained as a result of the play existing between said cylindrical bore and the triangular portion 23e of the shank 23b.

The double valve 23 is resiliently urged against its lower seat by a spring 24 the initial tension of which is adjustable by means of a threaded plug 25 and of a lock-nut 26 (Figs. 2 and 3).

When the pressure in the discharge collector formed by the conduits 2c, that is to say in the utilization circuit, increases and slightly exceeds the pressure exerted by the spring 24, the liquid contained in the conduit 72 communicating with the recess 2e slightly raises the double valve 23 until the cylindrical portion of the shank 23c rises out of the corresponding cylindrical bore. At that time, the liquid penetrates into the chamber 23d housing the double valve head 23a. The cylindrical portion of the shank 23b closes the corresponding cylindrical bore. The cross-section of the cylindrical bore within which moves the cylindrical portion of the shank 23b being greater than that of the cylindrical bore through which moves the cylindrical portion of the shank 23c, the action of the liquid tends to overcome the resistance of the spring 24. Said spring 24 suddenly yields and the sudden movement or "snap action" of the double valve head 23a urges said head against its upper seat. The liquid suddenly flows from the chamber 23d through the passage 2f and the circular channel 27 to the passages 2f communicating with the chambers 2p of the cylinders 1c between the shoulders 1a and 1g, whereby all the pistons 1 are pushed outward towards the plugs 18a; the suction is thus automatically checked and the pump is automatically and instantaneously cut out.

When considering the step where all the pistons are locked, i. e. where the double valve 23 has its valve head 23a urged against its upper seat, if the pressure falls slightly below said predetermined value in the recess 2e, the double valve head 23a is urged back on its lower seat by the spring 24. The cylindrical portion of the shank 23c closes the corresponding cylindrical bore, thus cutting out the communication between the recess 2e and the passage 2f. Then, the cylindrical portion of the shank 23b rises out of the corresponding cylindrical bore so that the communication between the passage 2f and the passages 2g via the chamber 23d is established. The displacement of the double valve 23 ends through a sudden movement or "snap action," then the pressure acts only on the cylindrical portion of the shank 23c which has a cross-section smaller than that of the cylindrical portion of the shank 23b. The liquid contained in the chambers 2p is discharged towards the supply tank through passages 2f, circular channel 27, passage 2f and conduits 2g communicating with the radial conduits 2d. The pistons 1 return into engagement with the annular member

7 of the eccentric 4 and the pump resumes operation.

The chief advantages of the improved pump as described consist in rendering unnecessary, on one hand, all conduits, flexible or not, disposed outside ordinary pumps and which require constant maintenance, and, on the other hand, manometric and electrical devices used in the known art to cause cutting out of the pump at a certain maximum pressure, these advantages being obtained whatever the characteristics of the pump employed.

In the forms of embodiment illustrated in Figs. 7 and 8, the hydraulic checking means employed is of the type of that described in connection with Figs. 1 to 6 and will not be described anew; the same numerals refer to similar elements as in Figs. 1 to 6.

In the form of embodiment illustrated in Fig. 20 7, each of the radial pistons 50 of the pump is cylindrical and comprises a cambered head 33 which normally engages a grooved ring 7 constituting the outer race of a needle bearing 8 the inner race of which is formed by the eccentric 4 keyed on the driving shaft 6. Each of said radial pistons 50 comprises an axial bore 30 communicating by a passage 31 with ports 50b provided near the inner end of the piston 50. These ports 50b communicate with a central chamber 30 25 74 provided in the casing 2. The passage 31 is normally closed by a valve member 19, such as a ball, when the piston 50 moves outwardly. This ball 19 is maintained in its housing by a washer 32 which bears against a shoulder of the axial bore 30 and on which acts a helical spring 51 the other end of which bears against the bottom of the axial recess of a threaded plug 52 constituting the cylinder head corresponding to piston 50. Said spring 51 tends to maintain the piston 50 in engagement with the ring 7.

According to the present invention, the piston 50 is located within the bore of a bushing 35 provided with two different diameters so as to form a shoulder 36 to allow for the operation of the hydraulic checking means as explained hereinafter. Said bushing 35 is slidably fitted in corresponding bores of the casing 2 and tightness of fit between the body 2 and the bushing may be provided by segments 37 for example.

Said bushing 35 is urged towards the center of the pump by a helical spring 38 bearing, at one end, against the upper face of said bushing 35 and, at the other end, against the threaded plug 52. The centerwards motion of said bushing 35 is limited by a collar 39 provided round the outer end of said bushing and which bears against a shoulder 40 provided in the casing 2. In this extreme position an annular chamber 41 is formed below the bushing shoulder 36. This chamber 41 communicates through a passage 2f and an annular chamber 27 with the hydraulic device controlling the cutting out of the pump, which is similar to that already described.

The bushing 35 is connected with the piston 50 through a transverse member 42 secured to the inner end of said bushing and passing through suitable apertures of the piston 50 which are formed, for example, as shown in Fig. 7 by two of the inlet ports 50b. On this member 42 and co-axially with the piston passage 31 is secured a needle or rod 43 the function of which will be explained hereinafter. In the normal position of the bushing 35, i. e. when its collar 39 bears against the casing shoulder

40 and the piston 50 is in innermost position as shown in Fig. 7, the needle 43 is not in contact with the ball 49 which then rests upon its seat. Furthermore a certain play is maintained between the member 42 and the upper end of the ports 50b.

A suitable relief valve 22 is located, as already described, at the outer portion of each cylinder 50c and a radial passage 2d is provided for the return of excess of liquid into the central suction chamber 74. The discharge of each cylinder is effected through a passage 2a.

In operation, the rotation of the shaft 6 of the eccentric 4 keyed on it causes successive displacements of the different pistons 50 towards the periphery of the casing 2, and consequently discharge of the liquid contained in the various cylinders through passages 2a. The suction is effected from the center suction chamber 74 through ports 50b and axial passages 31 provided within the various pistons 50, during the return stroke of said pistons under the effect of springs 51.

When pressure in the discharge collector, i. e. in the utilization circuit, exceeds a predetermined value, it has been seen that the device controlling the automatic cutting out of the pump, called the hydraulic checking means and above described (double valve 23 and its seats), admits liquid under pressure into the passages 2f. This liquid penetrates into the annular chamber 41 and moves the bushing 35 in the direction of the arrow f. When this displacement starts, the needle 43 raises the ball 49 from its seat and the liquid contained in the cylinder may return to the central suction chamber 74. Thereafter, the member 42 is brought to bear on the outer end of the port 50b and the bushing 35 then draws the piston 50 towards its outermost position or checking position. In this position the control eccentric 4, while revolving, no longer actuates that piston, thus effecting automatic cutting out of the pump.

As soon as the discharge pressure of the pump returns to normal, the piston-valve 23 returns to its normal position in which it causes the passages 2f to communicate with the suction through circular channel 27 and conduits 2f1, 2g and 2d (Fig. 2). The bushings 35 are brought back by the springs 38 to their innermost positions; their collars 39 bear against the casing shoulders 40 and the pistons 50 return under the action of the springs 51 to their innermost positions into engagement with the ring 7 mounted on the eccentric 4; the pump is then once more operative.

Fig. 8 shows another form of embodiment of the hydraulically controlled checking device acting on the various radial pistons of the pump. Each of the pistons 55 is cylindrical and slides directly in a suitable radial bore 55c formed in the casing 2. Said piston 55 is driven (as in the case of the embodiments illustrated in Figs. 1 and 7) by a shaft 6 provided with an eccentric 4 and is urged into engagement with said eccentric by a spring 56 bearing, at one end, on a threaded plug 57 constituting the head of the cylinder end, and, on the other end, bearing on a threaded ring 45 screwed into a tapered portion of the axial piston bore 58. Said bore 58 communicates with the central chamber 74 through a passage 59 and a transverse port 55b provided in the piston. A valve constituted for example by a ball 49 normally obturates the passage 59 under the effect of a conical spring

46 bearing against said ball and against the inner face of the threaded ring 45.

At its periphery, the piston 55 has a groove 47 which is substantially semi-circular in cross-section and with which may engage the substantially hemispherical end of a small piston 48 when the piston 55 is in outermost position. Said small piston 48 is tightly mounted in a corresponding bore 49 provided in the casing and the axis of which is perpendicular to the cylinder axis. Into said bore 49 opens the passage 2f connected to the hydraulic checking device.

In operation, when the discharge pressure of the pump exceeds a predetermined value, the hydraulic checking device, as above described in connection with Figs. 1 to 6, becomes operative and admits fluid under pressure into the various passages 2f each of which corresponds to one of the cylinders. The liquid urges back the small pistons 48 against the pistons 55 and, as soon as the latter in succession attain their outermost position under the action of the eccentric 4, the spherical end of the corresponding small piston 48 engages the corresponding peripheral groove 47 of each of those pistons. The latter are thus maintained in this position corresponding to the cut-out condition of the pump so long as pressure is applied on said small pistons.

As soon as the discharge pressure of the pump returns to normal, the piston valve 23 returns to its normal position. Passages 2f are then put in communication with the suction through channel 27 and conduits 2f1, 2g and 2d (Fig. 2). At that instant the small pistons 48 are no longer forced against the piston 55 by the liquid pressure and they are pushed back into their recesses by means of the pistons 55 themselves acting on their spherical ends, while said pistons 55 are brought back into engagement with the eccentric under the action of the springs 56; the pump is therefore once more operative.

In the various forms of embodiment above described and illustrated, it will be seen that by simply removing the threaded plugs 57, the corresponding pistons 55 may easily be removed, and in the form of embodiment illustrated in Fig. 7, the bushing 35, wherein the pistons slide, may also be removed.

Such disposition provides for the possibility of ready dismantling of the pump and replacement of the bushings 35 and of pistons 50, wear chiefly occurring between the bushings and the pistons in the case of embodiment illustrated in Fig. 7.

What I claim is:

1. In a radial-piston pump for liquids, a casing having an inlet chamber, an outlet port and uniformly spaced radial cylinders the inner ends of which are in communication with said chamber, means for closing the outer ends of said cylinders, a tubular piston in each of said cylinders and removable through the outer end thereof, said pistons having closed inner ends projecting into said chamber and inlet ports to connect the same with said chamber, a central shaft journalled in said casing and rotatable within said chamber, an eccentric on said shaft having driving contact with said closed inner ends of said pistons, check valves located within said respective pistons to prevent return of the liquid through the same toward said chamber, discharge ducts connecting the outer ends of said cylinders with said outlet port, resilient means for urging said pistons against said eccentric,

hydraulic means for immobilizing said pistons in their outermost positions corresponding to the end of the compression stroke when the delivery pressure of the pump exceeds a predetermined value, whereby said pump is thereupon automatically and instantaneously put out of action even though said shaft continues to be actuated by a continuous rotational movement at a suitable angular velocity, and hydraulic means for actuating said immobilizing means, said hydraulic means comprising a set of interconnected conduits respectively connected with said immobilizing means, means for connecting said set of conduits with said discharge ducts when the delivery pressure of the pump exceeds said predetermined value, and means for connecting said set of conduits with said inlet chamber when said pressure falls slightly below said predetermined value.

2. In a radial-piston pump for liquids, a casing having an inlet chamber, an outlet port, uniformly spaced radial cylinders the inner ends of which are in communication with said chamber, a set of three aligned chambers whereof the first and the third chambers are respectively in communication with said inlet chamber and said outlet port, and two aligned channels respectively connecting said first and third chambers with the second chamber of said set, the diameter of the channel interconnecting the first and second chambers being slightly greater than that of the other channel, means for closing the outer ends of said cylinders, a tubular piston in each of said cylinders and removable through the outer end thereof, said pistons having closed inner ends projecting into said inlet chamber and inlet ports to connect the same with said chamber, a central shaft journalled in said casing and rotatable within said inlet chamber, an eccentric on said shaft having driving contact with said closed inner ends of said pistons, check valves located within said respective pistons to prevent return of the liquid through the same toward said inlet chamber, discharge ducts connecting the outer ends of said cylinders with said outlet port, resilient means for urging said pistons against said eccentric, hydraulic means for immobilizing said pistons in their outermost positions corresponding to the end of the compression stroke when the delivery pressure of the pump exceeds a predetermined value, whereby said pump is thereupon automatically and instantaneously put out of action even though said shaft continues to be actuated by a continuous rotational movement at a suitable angular velocity, a double-valve located in said second chamber and having two aligned opposite shanks ended by triangular sections and which are reciprocally guided by said channels, resilient adjustable means for normally maintaining said double-valve in the position for which the communication between said second and third chambers is closed, a set of interconnected conduits respectively connected with said immobilizing means, and a passage connecting said second chamber with said set of interconnected conduits, so that, when the delivery pressure of the pump exceeds said predetermined value, the double-valve suddenly closes the communication between the first and second chambers and opens the communication between the third chamber and the set of interconnected conduits via the second chamber and the passage, whereby said immobilizing means are operative, while, when said delivery pressure falls slightly below said predetermined value, said

resilient adjustable means suddenly returns said double-valve to its normal position.

3. A radial-piston pump for liquids, according to claim 2, wherein each piston is formed with a shoulder in the upper part thereof, said shoulder being associated with a flange formed on the inner surface of the corresponding cylinder for providing a hydraulic chamber between said flange and said shoulder, the corresponding conduit of the set of interconnected conduits opening in said chamber, whereby the latter acts as immobilizing means.

4. A radial-piston pump for liquids, according to claim 2, wherein the immobilizing means comprises reciprocable bushings surrounding the pistons, located in the cylinders and formed with circular grooves and with shoulders, said shoulders being associated with flanges formed on the inner surfaces of said cylinders for providing hydraulic chambers between said shoulders and said flanges, the conduits of the set of interconnected conduits respectively opening in said chambers, said bushings further having seal rings located in said grooves, rods fixed on the inner part of said bushings crossing the inlet ports for connecting said pistons with said bushings when the latter are operative, and means fitted on said rods for opening the check valves at the beginning of the outward displacement of said bushings.

5. A radial-piston pump for liquids, according to claim 2, wherein the casing is formed, for each cylinder, with a cylindrical recess perpendicular to and opening within said cylinder, the corresponding conduit of the set of interconnected conduits opening in said recess, and wherein the immobilizing means comprises small pistons reciprocable in said recesses under the action of the pressure existing in said set of conduits and the heads of which are adapted to penetrate in suitable grooves formed on the pistons when said pressure exceeds the predetermined value, and means for allowing the disengagement of said small pistons from said grooves when said pressure falls slightly below said predetermined value.

6. In a two stage radial-piston pump for liquids, a casing having an inlet chamber, an outlet port, two sets of uniformly spaced radial cylinders equal in number and respectively located in parallel planes, the inner ends of said cylinders being in communication with said inlet chamber, a set of three aligned chambers whereof the first and the third chambers are respectively in communication with said inlet chamber and said outlet port, and two aligned channels respectively connecting said first and third chambers with the second chamber of said set, the diameter of the channel interconnecting the first and second chambers being slightly greater than that of the other channel, means for closing the outer ends of said cylinders, two sets of pistons respectively in the cylinders of said two sets of cylinders and removable through the outer ends thereof, said pistons having closed inner ends projecting into said inlet chamber, the pistons of the first set being tubular and having inlet ports to connect the same with said inlet chamber, a central shaft journalled in said casing and rotatable within said inlet chamber, two eccentrics on said shaft having an angular shifting substantially equal to 180° and respective driving contact with said closed inner ends of the pistons of said two sets, check valves located within the respective pistons of the first set to prevent return of the liquid through the same

toward said inlet chamber, connecting ducts for connecting two by two the outer ends of the cylinders of said two sets of cylinders, resilient means for urging the pistons of the first set against the corresponding eccentric, check valves located at the junction of the connecting ducts with the cylinders of the second set to prevent return of the liquid through the same toward the cylinders of the first set, discharge ducts connecting the outer ends of the cylinders of said second set with said outlet port, check valves inserted in said discharge ducts, hydraulic means for immobilizing the pistons of the first set in their outermost positions corresponding to the end of the compression stroke when the delivery pressure of the pump exceeds a predetermined value, whereby said pump is thereupon automatically and instantaneously put out of action even though said shaft continues to be actuated by a continuous rotational movement at a suitable angular velocity, means for preventing an excess of pressure in the cylinders of the first set in the event one at least of the pistons of the second set be seized within the corresponding cylinder, a double-valve located in said second chamber and having two aligned opposite shanks ended by triangular sections and which are reciprocally guided by said channels, resilient adjustable means for normally maintaining said double-valve in the position for which the communication between said second and third chambers is closed, a set of interconnected conduits respectively connected with said immobilizing means, and a passage connecting said second chamber with said set of interconnected conduits, so that, when the delivery pressure of the pump exceeds said predetermined value, the double-valve suddenly closes the communication between the first and second chambers and opens the communication between the third chamber and the set of interconnected conduits via the second chamber and the passage, whereby said immobilizing means are operative; while, when said delivery pressure falls slightly below said predetermined value, said resilient adjustable means suddenly returns said double-valve in its normal position.

7. A two-stage radial piston pump for liquids, according to claim 6, wherein each piston of the first set is formed with a shoulder in the upper part thereof, said shoulder being associated with a flange formed on the inner surface of the corresponding cylinder for providing a hydraulic chamber between said flange and said shoulder, the corresponding conduit of the set of interconnected conduits opening in said chamber, whereby the latter acts as immobilizing means.

8. A two-stage radial piston pump for liquids, according to claim 6, wherein the immobilizing means comprises reciprocable bushings sur-

rounding the pistons of the first set, located in the cylinders of the first set and formed with circular grooves and with shoulders, said shoulders being associated with flanges formed on the inner surfaces of said cylinders for providing hydraulic chambers between said shoulders and said flanges, the conduits of the set of interconnected conduits respectively opening in said chambers, said bushings further having seal rings located in said grooves, rods fixed on the inner part of said bushings crossing the inlet ports for connecting said pistons of the first set with said bushings when the latter are operative, and means fitted on said rods for opening the check valves corresponding to said pistons of the first set at the beginning of the outward displacement of said bushings.

9. A two-stage radial piston pump for liquids, according to claim 6, wherein the casing is formed, for each cylinder of the first set, with a cylindrical recess perpendicular to and opening within said cylinder, the corresponding conduit of the set of interconnected conduits opening in said recess, and wherein the immobilizing means comprises small pistons reciprocable in said recesses under the action of the pressure existing in said set of conduits and the heads of which are adapted to penetrate in suitable grooves formed on the pistons of the first set when said pressure exceeds the predetermined value, and means for allowing the disengagement of said small pistons from said grooves when said pressure falls slightly below said predetermined value.

10. A two-stage radial piston pump for liquids, according to claim 6, wherein the means for preventing an excess of pressure comprises relief valves respectively connected with the outer end of the cylinders of the first set, said valves having springs adapted to exert thereon a pressure greater than the normal delivery pressure of the pistons located in said cylinders, and ducts for respectively connecting said relief valves with the inlet chamber.

GEORGES PAUGET.
